UNITED STATES PATENT OFFICE.

JOSEPH SCHNARR, OF NEWARK, NEW JERSEY.

DESIGN FOR A CLOCK-CASE.

SPECIFICATION forming part of Design No. 24,331, dated May 28, 1895.

Application filed January 22, 1895. Serial No. 535,824. Term of patent 14 years.

To all whom it may concern:

Be it known that I, JOSEPH SCHNARR, residing at Newark, in the county of Essex and State of New Jersey, have invented and produced a new and original Design for Clock-Cases, of which the following is a specification, reference being had to the accompanying drawings, illustrating the same and forming a part thereof.

10 My invention relates to designs for clock cases and is more especially adapted for small household or mantel clocks.

15 The object is to provide a clock case of the class specified which shall be odd, ornamental and attractive in appearance.

The invention consists in the design hereinafter described and illustrated by the accompanying drawings, which form a part of the specification.

In the said drawings, Figure 1 is a view showing my design in front elevation, and Fig. 2 a view showing the same in side elevation.

The leading feature consists in a small or miniature case of metal or wood formed and proportioned like an upright piano case. A 25 represents the case. Within an opening in the field of the upper front panel of said case A the clock face B is placed.

What I claim is—

The design for a clock case substantially as 30 herein shown and described.

In testimony that I claim the invention above set forth I affix my signature in presence of two witnesses.

JOSEPH SCHNARR.

Witnesses:

L. H. SCOTT,
P. MC CONVILLE.
